UNITED STATES PATENT OFFICE.

GUSTAVE BURLAT, OF VILLEURBANNE, FRANCE.

MOP.

Application filed May 7, 1926, Serial No. 107,512, and in France May 12, 1925.

Mops with detachable fringes comprise a frame on which the fringe is secured, the fringe being removable therefrom in order that it may be easily washed or changed as required. This detachable connection has hitherto been effected by means of buttons or hooks fastened to the fringe and adapted to be engaged in corresponding openings provided in the frame or vice versa.

After prolonged use and successive washings the fringe becomes shorter or longer according to the treatment to which it has been subjected and in the known constructions when it is desired to again secure the fringe to the frame, the buttons or hooks no longer coincide with their respective openings and the attachment of the fringe is difficult or impossible.

The present invention has for its object to provide a mop head with detachable fringe the essential feature of which consists in the means adopted to secure the fringe on the frame or head. For this purpose the lower surface of the frame is provided with an interrupted or continuous groove of curvilinear contour in which the edge of the fringe is placed. The edge is thickened for this purpose and forms a pad which engages in the groove from which it can only be removed by an endwise sliding movement.

Consequently however much the fringe may become lengthened or shortened the edge thereof can always be inserted in the said fixing groove; it is held firmly therein owing to the sinuous shape of the groove and without the necessity for male and female engaging members.

The accompanying drawing illustrates by way of example, two forms of construction of my improved mop head.

Fig. 1 is a perspective view of the fringe, with part in section,

Fig. 2 is a plan view of the under side of the frame,

Fig. 3 is a section taken on line 3—3 of Fig. 2,

Fig. 4 is a plan view of the top of the frame,

Fig. 5 is a section on line 5—5 of Fig. 4,

Fig. 6 is a section on line 6—6 of Fig. 2, the fringe being in place,

Fig. 7 is a detail view of a modification and illustrates a method of assembling the various parts of the frame,

Fig. 8 is an underside plan view of a modified form of construction of the frame,

Fig. 9 is a section on line 9—9 of Fig. 8,

Fig. 10 is a diagrammatic view showing the manner in which the fringe is arranged in the frame.

The fringe *a* (Fig. 1) is mounted on an edging *b* which connects the strands of the fringe and inside which is placed a pad *c* of cord or any other material.

The edging is thus in the form of a long pad from which the fringe hangs.

The frame, illustrated in Fig. 2, is formed of two sheets of metal *d*, *e* of suitable section and the assembling of which forms underneath an undercut groove comprising several portions *f*, *g*, *h*, *i* which are not in continuation of one another.

In order to put the fringe in place one of the ends of its padded edge is pushed into the groove *f* in the direction of the arrow *j*. The other end of the padded edge which is thickened, is stopped at *k* and serves as a fixing point. Then the edge is passed into the grooves *g*, *h* and finally into the middle groove *i*.

In order to remove the fringe the reverse operation is performed.

The two plates *d*, *e* can be connected by means of rivets or by bolts and nuts *l*.

In the modification of construction, illustrated in Fig. 7, the plates *d*, *e* are connected by means of bolts *l* with winged or milled-headed nuts *m*. In this way, by unscrewing the nuts the plates *d*, *e* can be slightly separated at the insertion of the fringe in order to facilitate this operation, as the thickness of the pad may not always be exactly uniform.

The mop-handle is fixed, for instance, in a socket *p* articulated on the upper part of the frame.

The groove can have any contour forming the best arrangement for the satisfactory distribution of the fringe.

Having now particularly described and ascertained the nature of my said invention and in what manner the same is to be performed, I declare that what I claim is:—

- 5 A mop fabric having a thickened flexible upper edge, and a frame having a perimetrical groove the walls of which are rigid and said groove having a restricted entrance slot and corresponding cross-sectionally in size

and shape with the said thickened upper edge of the mop so that said thickened upper edge is engaged and held between said walls, and in which said edge is arranged by sliding movement longitudinally of said thickened edge. 10

In witness whereof I affix my signature. 15

GUSTAVE BURLAT.
